FORCING BAG

John MacManus, 143-16 22nd Road,
Whitestone, N.Y. 11357

Filed Jan. 5, 1971, Ser. No. 104,195

Claims priority, application Great Britain July 9, 1970

The portion of the term of the patent subsequent to
Sept. 7, 1985, has been disclaimed

Term of patent 14 years

Int. Cl. D9—05

U.S. Cl. D9—194

FIG. 1 is a front elevation of a forcing bag embodying my new design, the rear elevation being a mirror image thereof;

FIG. 2 is an enlarged fragmentary front elevation of the forcing bag, the rear elevation being a mirror image thereof;

FIG. 3 is an enlarged fragmentary side elevation of the forcing bag, the other side being a mirror image thereof; and

FIG. 4 is a cross-sectional view taken along line X—X of FIG. 2.

I claim:

The ornamental design for a forcing bag, substantially as shown and described.
